Primary Examiner — Karen Kearney*Assistant Examiner* — Debra Callahan(74) *Attorney, Agent, or Firm* — Wolf, Greenfield & Sacks, P.C.(57) **CLAIM**

The ornamental design for a recreational flotation device, as shown and described.

DESCRIPTION

FIG. 1 is a rear perspective view of a recreational flotation device showing my new design;

FIG. 2 is a front elevational view thereof;

FIG. 3 is a top plan view thereof;

FIG. 4 is a right side elevational view thereof; the left side elevational view being an identical mirror image thereof;

FIG. 5 is a bottom plan view thereof; and,

FIG. 6 is a rear elevational view thereof.

The broken lines in FIG. 5 depict an inflation valve and form no part of the claimed design.

1 Claim, 3 Drawing Sheets(56)
